UNITED STATES PATENT OFFICE.

TAYLOR E. DANIELS, OF CHICAGO, ILLINOIS.

STEAM FEED COOKER AND DRIER.

SPECIFICATION forming part of Letters Patent No. 235,343, dated December 14, 1880.

Application filed September 28, 1880. (No model.)

To all whom it may concern:

Be it known that I, TAYLOR E. DANIELS, a citizen of the United States, residing at Chicago, in the county of Cook and State of Illinois, have invented certain new and useful Improvements in Steam Feed Cookers and Driers; and I hereby declare the following to be a full, clear, and exact description thereof, reference being had to the accompanying drawings, of which—

Figure 1 is a side elevation of the apparatus with certain portions broken away, showing the interior construction; Figs. 2 and 3, opposite end views; Fig. 4, a vertical cross-section of the apparatus; and Fig. 5, a detail section showing the construction of the jet-pipes which convey steam into the cooking-cylinder.

My present invention relates to certain improvements upon the apparatus described in Letters Patent of the United States No. 225,511, granted to me March 16, 1880.

These improvements consist, first, in employing, instead of the vertical cooker with cone-like steam-discharging stirrers described in the Letters Patent aforesaid, one or more horizontal screw-conveyers inclosed within cylinders similar to those employed in the drier, and communicating with the said cylinders of the drier in the same manner as the latter communicate with one another, together with appliances for injecting steam into the interior of the grain as it is carried through the cylinder; secondly, in providing a hot-air flue upon the lower face of each cylinder of the drier, communicating with the interior of said cylinder through perforations in said cylinder; thirdly, in the exhaust which I employ for carrying off the vapors which arise within the cylinders of the drier; and, furthermore, in certain details of construction—all as hereinafter more fully set forth.

In the drawings, A is the case of the apparatus; B B, the three pairs of horizontal cylinders of the drier communicating with one another at alternate ends through vertical passages v, and the lowest pair having discharge-chutes v', all this being substantially the same as in my said former Letters Patent, and hence requiring no particular description here.

C C are the screw-conveyers lying within

the cylinders B, and having hollow shafts journaled into the ends of the case A, and revolved by means of gear-wheels u, operated in common by a pulley upon the shaft D, all this being also substantially as described in my said former Letters Patent, except that I now perforate the shafts of the conveyers and force hot air into them instead of steam, as will be hereinafter explained.

E E are gates of steam-pipe, which I now prefer to arrange edgewise upon both sides of the cylinders B, as shown, and preferably curved, so as to lie against the cylinders instead of above and below them, as formerly, their function, however, remaining unchanged.

The functions and operation of this much of my apparatus being fully described in the specification of my said Letters Patent No. 225,511, I shall now proceed to describe my present improvements, beginning with the cooker.

B' B' are two horizontal hollow cylinders extending from end to end of the case A, and corresponding to those of the drier below them. Each has a feed-chute, t, at one end, and communicates with the cylinder B beneath it by means of a chute, v, at the opposite end, in the same manner as the cylinders B communicate with one another.

C' is a screw-conveyer within each cylinder B', and journaled in the ends of the case A. Both the shaft and blade of this conveyer are hollow, and their interiors communicate, as clearly shown in Fig. 4. The blade of this conveyer is provided with perforations s.

F is a pipe, which is to be connected with a suitable steam-generator, and branches of this pipe lead both into the hollow shafts of the screw-conveyers C' and into the uppermost gates of pipe E.

G G are pipes leading from the steam-pipe F, and extending across the interior of the case A parallel with the cylinders B', and a short distance below them. The interiors of the pipes G and cylinders B' communicate with each other through jet-pipes H, screwed into bushings r upon each, as clearly shown in Fig. 5. The various shafts and pipes are provided at their points of junction with the steam-pipe F, or near the same with cut-off valves q, and all find an outlet by way of the

waste-pipe K, at the opposite end of the apparatus.

The cylinders B' are provided along their lower faces at points intermediate between 5 the jet-pipes H with perforations p, and L is a curved drip-pan below the said cylinders, inclined from each end to a waste-pipe, o, which leads out through the bottom of the case.

10 The screw-conveyers C' are provided with pulleys n on the outlet ends of their shafts, and are rotated by means of belts m, connecting the pulleys n with pulleys n' on the corresponding ends of the shafts of the central 15 screw-conveyers of the drier.

The construction of the cylinders B and their attendant parts comprising the drier is as follows: The lower faces of the cylinders B are provided with perforations p', and flues M, 20 semicircular in form, fit close against the cylinders covering the said perforations.

The hollow shafts of the screw-conveyers C are provided with perforations s', and each is connected by means of a pipe, l, having a packing-joint adapted to permit the revolution of 25 the conveyer with a hot-air shaft, N. Branch pipes k from these hot-air shafts lead also into the flues M, which latter are closed at their opposite ends, and thus open only into the 30 cylinders B through the perforations p'.

O O are horizontal pipes, one above each of the cylinders B of the drier, opening through the case A at one end and leading into a draft-flue, P, at the other; and i i are short pipes 35 sloping in the direction of the draft, as shown in Fig. 1, leading from the pipes O into the tops of the cylinders B.

The operation is as follows: Steam is admitted, by way of the pipes F, into the interior 40 of the screw-conveyers C', and also into the pipes G and gates of pipe E. At the same time hot air is forced, by way of the stand-pipes N and branch pipes thereof, into the hollow perforated shafts of the screw-convey- 45 ers C, and into the flues M. The machinery having been set in motion, the material to be cooked is fed from suitable hoppers into the cylinders B' by way of the chutes t, when it is immediately taken up by the conveyers 50 therein and carried along until it reaches the chute v, when it drops into the uppermost cylinder of the drier, along which it passes until it falls into the next cylinder, and so continues to do until it emerges from the discharge 55 v', as described in my former Letters Patent. While passing along the cylinder B' it is subjected to the action of steam passing into the interior of said cylinder both through the perforations s in the blade of the conveyer and 60 through the jet-pipes H.

Those varieties of grain requiring a greater degree of cooking should be fed into one of the cylinders B', and those requiring a less into the other, and the flow of steam so regulated by 65 means of the valves q as to admit a proportionately greater volume into the latter cylinder

than the former, or else the flow either through the conveyer or the pipe G may be wholly cut off, and steam admitted only through the other. The steam finds an outlet from each into the 70 exhaust-pipe K, and the moisture which collects on the bottom of the cylinder B' drips through the openings p into the pan L, and is carried off by the pan o.

Upon entering the drier, and while passing 75 back and forth through the cylinders of the same, the cooked material is subjected to the action of hot air both from within by way of the perforations s' in the shafts of the conveyers and from without by way of the perforations p', leading from the flues M. The gates of pipe E add still further to the heat to which the grain is subjected, lying, as they do, close to the cylinders.

If desired, screw-conveyers like those in 80 the cooker—that is, with hollow blades as well as hollow shafts—may be used also in the drier with or without the addition of perforations in the shafts. In this case, of course, hot air would be passed through them instead of 85 steam. The shaft as well as the blade may be perforated when used in the cooker also, if preferred. It should be remarked that the chief feature of the conveyer C' lies in the intercommunicating hollow shaft and blade, and that 90 the perforations therein might, under certain circumstances, as in the drier, for example, be wholly dispensed with.

The vapors which are created within the cylinders B by the drying process pass into 95 the pipes O through the oblique tubes i and escape from the apparatus by way of the draft-flue P.

If desired, a forced current may be created 100 through the pipes O and draft-flue P by connecting the former with the hot-air shafts N, and thus accelerating the escape of the vapors; but it is not thought that this will be found necessary.

What I claim as new, and desire to secure 110 by Letters Patent, is—

1. In a feed-cooker, the combination of the cylinder B', screw-conveyer within the same, steam-pipe G, below the said cylinder, and jet-pipes H, connecting the interiors of said steam- 115 pipe and cylinder, substantially as and for the purpose set forth.

2. In a feed-cooker, the combination, with the hollow cylinder B', having perforations p in its lower face, screw-conveyer C', steam-pipe F, pipe G, and jet-pipes H, all as shown, of the drip-pan L and waste o', substantially 120 as described.

3. A screw-conveyer having a perforated hollow shaft, in combination with an inclosing cylinder or case, and with a pipe adapted 125 to convey hot air into the interior of said hollow shaft, substantially as described.

4. In combination with the cylinder B, having perforations in its lower face, and with a 130 screw-conveyer within said cylinder, the flue M, pipe k, for conveying hot air into said flue,

and draft-flue P, communicating with the interior of the cylinder B, the whole being constructed and arranged substantially as described.

5 5. In combination with the cylinder B, screw-conveyer within the same, and means for forcing hot air into said cylinder, the pipe

O, tubes *i*, and draft-flue P, the whole being constructed and arranged to operate substantially as described.

TAYLOR E. DANIELS.

In presence of—

A. M. KEANE,
JOHN ALANSON.
